UNITED STATES PATENT OFFICE.

WILLIAM MACQUARIE MALONE, OF WANDI NARRABRI, NEW SOUTH WALES,
AUSTRALIA.

FASTENING FOR BOOTS AND SHOES AND LEGGINGS, &c.

No. 856,714.

Specification of Letters Patent.

Patented June 11, 1907.

Application filed March 7, 1906. Serial No. 304,662.

To all whom it may concern:

Be it known that I, WILLIAM MACQUARIE MALONE, of Wandi Narrabri, in the State of New South Wales and Commonwealth of Australia, journalist, have invented Improved Fastenings for Boots and Shoes and Leggings and the Like, of which the following is a specification.

This invention relates to fastenings for boots, shoes, leggings and other articles in which two edge portions or flaps are required to be held together against a normal tendency to separate and the invention has for its object to provide a simple, convenient and suitable fastening device as a substitute for laces, buttons and the like which shall at the same time present an elegant and finished appearance.

Generally speaking the invention consists of a series of retaining plates secured inside the adjacent flaps, the plates of each flap being provided with outwardly projecting and reversely bent retaining lips adapted to be engaged by suitably formed clips or holders which are fastened to the under side or face of a flexible strip or tongue of leather or other suitable material which when drawn into locking or operative position serves to cover up the space or crack between the opposed edges of the article to be secured. These and other features characterizing my invention will be more particularly described and defined in the specification and the claims forming part thereof.

In order to illustrate how this invention may be carried out in practice reference will now be made to the drawings herewith in which

Figure 1 is a perspective view of a shoe having this improved fastening and showing this fastening as it would appear in the act of fastening the shoe. Fig. 2 is a partial similar view of the same showing the fastening complete. Fig. 3 is an inside view of the sliding keeper and Fig. 4 a face view of the receiving slides. Fig. 5 being a similar view to Fig. 4 showing a modified construction of catch or holder on said receiving slides.

The receiving slides are shown as made in sections being formed of clips or turned-over pieces having bases 6, grooves 7 and lips 8. The base 6 is perforated for the sewing of the same to the shoe between the outer material

and its lining exposing only the grooves 7 and the lips 8.

The sliding keeper is formed of a series of similar clips having bases 9 and lips 10 said lips being formed in a dead curved end 11 on the lowermost of the clips to form a stop to limit the upward movement of the keeper. 60 These clips are sewed by perforations to a continuous strip of leather or kid or the like with a tab 12 at the top.

The clips forming the receiving slide and the sliding keeper may be separated as shown 65 in the drawings. The corners of the lips are rounded to facilitate the sliding and the grooves have curved corners to insure smooth running.

The fastening clips may be formed in any 70 suitable way of any appropriate material and are attached to the leather or fabric of which the article on which they are used is made in any suitable manner such for example as by stitching as indicated in the drawings.

In the drawings there is shown on the shoe a loop or keeper 13 which provides a covering for the bottom end of the sliding keeper when in its normal fastening position and forms a guide for said keeper when in the act 80 of fastening and further forms a holding device for retaining the keeper permanently attached to the shoe.

As an extra precaution and to prevent any slipping of the sliding keeper from its fastening position a catch or holder is provided. This holder is shown in Fig. 4 as consisting of a spring 14 riveted to the top clip and having upon it a pin or pintle 15 adapted to take in a socket 16 on the top clip of the sliding-keeper. 90 In Fig. 5 this catch or holder is shown as consisting of a pin or pintle or catch 15 in the metal of the uppermost clip which catch is adapted to take into a corresponding depression 16 in the metal of the uppermost clip of 95 the sliding keeper. In both cases the catch is released by pressure toward one another of the clips on either edge while pressure is applied to the sliding keeper to release it.

It is easily perceived that when the sliding keeper is withdrawn by means of force applied downwardly by means of the tab 12 the lips 10 of the sliding keeper run in the grooves 7 under the lips 8 of the clips forming the receiving slides and running off the lowermost 105 clips unfasten the shoe. To fasten the shoe

the sliding keeper is drawn upwardly by means of the tab 12 the lips 10 of its clips taking in the grooves 8 of the clips forming the receiving slide and so drawing the edges 5 of the boot upper together. When the pindle 15 reaches its socket 16 it catches therein and acts as a self-locking detent to hold the fastening in place.

What I claim as my invention is:—

- 10 1. A device of the class described embracing in its construction the two opposed flaps to be fastened together, each flap having secured to itself a series of sheet metal plates formed with outwardly turned flanges forming 15 clips, a flexible leather tongue provided with a series of sheet metal plates having inwardly turned flanges extending parallel to each other and arranged to slidably engage and interlock with said outwardly turned 20 flanges, the lowermost sheet metal plate hav-

ing its lowermost edge turned in to form a stop for engaging the lowermost clips secured to said flaps, substantially as described.

2. A device of the class described embracing in combination two opposed flaps to be fastened together, said edges being provided with retaining devices bent to form longitudinal grooves or channels, a keeper adapted to interlock with said retaining devices and having sliding engagement therewith, and a self-locking detent for retaining said keeper in normal position against accidental displacement, substantially as described.

In testimony whereof I have signed my name to this specification in the presence of 35 two subscribing witnesses.

WILLIAM MACQUARIE MALONE.
